UNITED STATES PATENT OFFICE.

FRANK R. BATCHELDER, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

POCKETED-CARRIER EQUIPMENT.

1,326,016.

Specification of Letters Patent. Patented Dec. 23, 1919.

Original application filed July 17, 1917, Serial No. 180,980. Divided and this application filed December 28, 1917. Serial No. 209,354.

To all whom it may concern:

Be it known that I, FRANK R. BATCHELDER, a citizen of the United States, residing at Worcester, in the county of Worcester, State of Massachusetts, have invented a certain new and useful Improvement in Pocketed-Carrier Equipments, of which the following is a specification, reference being had therein to the accompanying drawings.

10 The invention is a division of that forming the subject of my application for U. S. Letters Patent filed July 17, 1917, Serial No. 180,980. It is an improvement in pocketed carriers made of woven material, of 15 the class embracing cartridge-carriers, hospital corps belts, medical officers' belts, and various other carriers having special adaptations. Such carriers comprise a plurality of pockets formed upon a supporting or 20 body-band and outstanding therefrom.

The invention relates, more particularly, to the pockets, pocket-covers or flaps, and means of securing the latter in closed condition, of carriers of the class just mentioned.

25 One special object of the invention is to produce carriers of woven material having pockets with smooth fronts. Another is to reduce the bulk and extent of projection of a pocket and its cover or flap when the latter is closed and fastened. Another is to 30 so apply and locate the covers or flaps and the fastener-devices therefor that they will be less likely to become caught upon different objects in the movements of the wearer.

35 of a carrier, and the covers or flaps pulled open. Another is to permit the use of light easy-action fastener-devices of greatly-reduced cost, such as could not be used if required to be positioned at the front of a 40 pocket on the prior form of cover or flap. Another is to reduce the amount of material contained in a pocket covering, and thereby lessen cost. Another is to improve the appearance of a carrier. Another is to provide 45 for double weather protection on top.

The invention consists, essentially, in a pocketed carrier of woven material having the pocket-front provided with a cover or flap member of woven material rising therefrom, adapted to be bent forward away from over the pocket and its contents into unclosed position, and to be folded rearward

over the top of the pocket and its contents into closed condition; and having also a second cover or flap member connected with the carrier at the rear of the pocket, adapted to fold forward and interlap with the said front cover or flap member to produce thereby double weather protection over the top of the pocket and its contents. A feature of invention is the location of the snap-fastener or other fastener-device at the top of the pocket instead of at the front thereof as heretofore.

Heretofore in usual practice the cover or flap of a carrier-pocket has been attached by one end thereof at the rear of the pocket with which it has been combined, and arranged to extend forward over the top of the pocket and its contents, and down in front of the pocket. One member of the usual fastener-device has been attached to the pocket-front and the other to the cover or flap near its free end, which latter usually has had its corners turned under and stitched to give a pointed finish. This general construction has a number of material drawbacks and disadvantages to which reference is made later herein, and which are overcome by the invention.

Various embodiments of the invention are shown in the drawings, in which latter,—

Figure 1 is a perspective view showing one of the pockets of a cartridge-carrier, and one of the said embodiments of the invention.

Fig. 2 is a similar view showing a slight modification.

Fig. 3 is a vertical section of the pocket of Fig. 1.

Fig. 4 is a vertical section of the pocket of Fig. 1, with its cover or flap members opened.

Figs. 5, 6, and 7 are vertical sections showing other embodiments of the invention.

Fig. 8 shows a portion of the body of a soldier wearing a cartridge-belt of well-known general character having covers or flaps in accordance with the invention.

Referring to the drawings,—

The pockets 1, 1, of Figs. 1, 2, and 8 may be woven integral with the supporting-bands or backings 2, 2, which is regarded as best in practice, or may be separately made in

approved manner (either by weaving them as pockets or by stitching them into shape) and attached to the said supporting-bands or backings.

5 The front cover or flap-member 3^b in Figs. 1, 2, 3, 4, 5, is a short piece of woven material which is attached by one end thereof to the pocket-front. The said piece is of a width bearing approved relations to that of 10 the pocket with which it is combined, and is of a length to enable it to extend rearward to the desired extent over the top of the pocket and its contents. In other words, the proportions of the front cover or flap-member are such as to afford in practice the required protection to the pocket-contents. The rear cover or flap member 5^a in Figs. 1, 2, 3, 4, etc., is a similar piece of woven material which is connected with the carrier 15 at the rear of the pocket, and as stated above is adapted to fold forward and interlap with the said front cover or flap-member to produce thereby the double weather protection over the top of the pocket and its contents. The fastening means for keeping the 20 cover or flap-members closed over the top of the pocket and its contents may vary in practice. In the drawings such means comprises fastener-devices 6^b, 7, of the well-known glove-fastener or ball-and-socket type, the members of which are applied to the front cover or flap-member and the rear cover or flap-member, respectively.

The rear cover or flap-member is shown 25 in most of the views as having the attaching end thereof inserted into a housing-slit formed in the supporting-band or backing 2, and secured therein by means of stitches 5^a. The said housing-slit may be dispensed 30 with if deemed advisable, and other fastening means than stitches may be employed in practice, if desired, such for instance as rivets or eyelets.

The front cover or flap-member in Figs. 45 3 and 4 is applied to the pocket-front by entering one end of the same into the pocket, and making the inserted portion fast to the pocket-front by stitches 4. The depth to which the inserted portion extends down 50 within the pocket may vary in practice, and such portion, if desired, may constitute an interior reinforce for the pocket-front, pocket-bottom, and pocket-back, or front and bottom, or front, in manner which will 55 be apparent to those skilled in the art. Other fastening means than stitches may be employed for securing the inserted portion of the front cover or flap-member, such for instance as rivets or eyelets. In some instances the attaching portion of the said 60 cover or flap-member may be applied exteriorly to the pocket-front.

Fig. 5 shows a modification in which the attaching end of the front cover or flap-member, 3^b, is entered into a housing-slit

formed in the pocket-front, and secured therein by means of stitches 4^a.

Fig. 6 shows a modification in which the pocket-front and pocket-back are without housing-slits, and the attaching ends of the 70 front cover or flap-member 3^b and rear cover or flap-member 5^b, respectively, are woven split or divided and applied so as to straddle the upper portions of the pocket-front and pocket-back, the parts being secured together 75 by stitches 5^c, (or other approved fastening means, if preferred).

Fig. 7 shows a modification in which the 80 front cover or flap-member 3^a, is woven integral with the pocket-front.

In the case of most of the embodiments of the invention that are shown in the drawings the rear cover or flap-member in the closed condition of the pocket overlies the front cover or flap-member, and the socket-member 6^b of the fastener-device is combined with the rear cover or flap-member, the coöperating stud-member 7 being combined with the front cover or flap-member. In Fig. 2 the front cover or flap-member 90 overlies the rear cover or flap-member in the closed condition of the pocket, the socket-member 6^b being applied to the front cover or flap-member, and the coöperating stud-member to the rear cover or flap-member. 95

A pocket-covering made in accordance with the invention does not extend down in front of the pocket, as in the case of covers or flaps heretofore provided in connection 100 with the pockets of carriers of the class to which the invention relates. The advantages of the invention are numerous and important, one therefore is the increase that is possible in the holding capacity of 105 the pockets, when desired, without material increase in the bulk and projection of the filled and covered or closed pockets. For instance, the present regulation cartridge belt has pockets carrying only two clips of 110 cartridges each, as in the drawings, and if the pockets were enlarged to hold three clips would be open to the objection that the filled pockets would stand out too far from the body of the wearer. The invention renders 115 it practicable to give the pockets capacity for holding three clips of cartridges, or a corresponding bulk of other articles.

Each of cover or flap-members shown in the drawings is a very short piece of woven 120 web. Such members require no expensive pointing. Each thereof is finished with a plain hem, as shown. If desired, even the hem may be dispensed with and the raw edge at the outer end of a cover or flap-member be merely whipped to prevent raveling.

When the front cover or flap-member is turned forward as in Fig. 4 it is out of the way at the front of the pocket and less 130

likely to interfere with access to the contents of the pocket and withdrawal of such contents.

What is claimed as the invention is:—

- 5 1. A pocketed carrier of woven material comprising a body-supported band or backing and a plurality of pockets outstanding therefrom in exposed position and having each pocket-front provided with a cover or
- 10 flap-member of woven material rising therefrom, adapted to be bent forward away from the supporting-band or backing and from over the pocket and its contents into unclosed condition, and to be folded rearward over the top of the pocket and its contents 35
- 15 into closed condition, and having also a second cover or flap-member connected with the supporting-band or backing at the rear of the pocket, adapted to fold forward and interlap with the said front cover or flap- 40 member, to produce thereby double weather protection over the top of the pocket and its contents, with inter-engaging fastener-members connected with the said cover or flap-members, respectively and located entirely at the top of the closed and fastened 45 pocket.
- 20 25 2. A pocketed carrier of woven material comprising a body-supported band or back-

ing and a plurality of pockets outstanding therefrom in exposed position and having each pocket-front provided with a cover or 30 flap-member of woven material rising therefrom, adapted to be bent forward away from over the pocket and its contents into unclosed condition, and to be folded rearward over the top of the pocket and its contents 35 into closed condition, and having also a second cover or flap-member connected with the supporting-band or backing at the rear of the pocket, adapted to fold forward and interlap with the said front cover or flap- 40 member, to produce thereby double weather protection over the top of the pocket and its contents, with inter-engaging fastener-members connected with the said cover or flap-members, respectively and located entirely at the top of the closed and fastened 45 pocket.

In testimony whereof I affix my signature in presence of two witnesses.

FRANK R. BATCHELDER.
